SHELF TOOTHBRUSH HOLDER

Francis A. Schmedinghoff, San Francisco, Calif.

Application August 3, 1950, Serial No. 177,482

4 Claims. (Cl. 211—86)

1

This invention relates to a supporting rack or holder, and more particularly to a rack for supporting a plurality of toothbrushes.

The object of the invention is to provide a rack which includes a plurality of toothbrush-supporting hook members which are detachably and adjustably connected thereto, the rack being constructed so that it can be readily attached to a shelf in such a manner as to not mar or disfigure the shelf in any way.

Another object of the invention is to provide a rack which has a plurality of toothbrush-supporting hooks detachably and adjustably connected thereto so that the hooks will remain immobile in their adjusted positions, the rack adapted to be positioned crosswise or lengthwise of a supporting shelf.

A further object of the invention is to provide a toothbrush holder which is extremely simple and inexpensive to manufacture.

Other objects and advantages will be apparent during the course of the following description.

In the accompanying drawings forming a part of this application, and in which like numerals are used to designate like parts throughout the same:

Figure 1 is a fragmentary side elevational view of a shelf with the toothbrush-supporting rack of the present invention mounted thereon;

Figure 2 is a top plan view of the toothbrush-supporting rack of the present invention;

Figure 3 is a bottom plan view of the rack;

Figure 4 is a perspective view of the rack of the present invention;

Figure 5 is a top plan view of a modified rack employing only one hook-receiving slot;

Figure 6 is a perspective view of another modified form of the toothbrush-supporting rack.

Referring in detail to Figures 1 through 4 of the drawings, the numeral 10 designates a portion of a shelf which may be a shelf in a bathroom or kitchen, while the numeral 11 designates a rack or clip. The rack 11 may be fabricated of any suitable material, and if desired, may be fabricated of metal or a suitable plastic. The rack 11 includes a body member 12 which is provided with a web 14, and projecting from the web 14 is a top wall 15. The top wall 15 is adapted to engage the upper surface of the shelf 10.

The body member 12 further includes a bottom wall 16 which is spaced below the top wall 15 and is of greater length than the latter, the top wall 15 and bottom wall 16 defining a clamp or clip, whereby the rack can be detachably mounted or connected to the shelf 10.

2

The bottom wall 16 is provided with a plurality of spaced slots which are indicated by the numeral 17, Figure 4. The slots 17 extend inwardly from one longitudinal edge of the bottom wall 16, and communicating with the inner portion of each of the slots 17 are cutouts 18, so that the slots are in the form or shape of a cross.

Dependently supported by the bottom wall 16 is a plurality of hook members 19. Each of the hook members 19 is the same and each embodies a shank 23 which has its lower end terminating in an arcuate finger 20 for engagement with the aperture in the handle of a toothbrush. Thus, the fingers 20 provide a means for supporting a plurality of toothbrushes in a sanitary and neat manner. Secured to the upper end of each of the shanks 23 is a circular disc 21, the disc 21 being arranged contiguous to the upper surface of the bottom wall 16, so as to prevent the hook members 19 from dropping from the bottom wall 16. Arranged below the disc 21 are cross bars 22, and the cross bars 22 seat in the slots 17 and in the cutouts 18 so that turning movement of the hook members 19 is prevented.

The hook members 19 are positioned in the bottom wall 16 before the rack 11 is connected to the shelf 10, so that it will be seen that the cross bars 22 can be moved out of the cutouts 18 and slots 17 if the hook members are to be rotated or adjusted about a vertical axis.

Referring to Figure 5 of the drawings, there is shown a slightly modified toothbrush-supporting rack which may also be fabricated of metal or a suitable plastic. The rack of Figure 5 is indicated generally by the numeral 25, and this rack is adapted to be used for supporting only one toothbrush. The rack 25 includes a top wall 26 and a bottom wall 27, these walls serving the same purpose as the previously-described walls 15 and 16. The bottom wall 27 is provided with a slot 28, the slot 28 extending inwardly from a transverse edge of the bottom wall, and communicating with the slot 28 are recesses or cutouts 29, the cutouts 29 and slots 28 serving the same purpose as the previously-described slots 17 and cutouts 18.

Referring to Figure 6 of the drawings, there is shown another modified toothbrush-supporting rack, which is indicated generally by the numeral 30. The rack 30 includes a web 32, a top wall 31 and a bottom wall 33. The bottom wall 33 and top wall 31 are adapted to be arranged on opposite sides of the shelf 10. The bottom wall 33 is provided with a plurality of spaced slots 34 which extend inwardly from one

longitudinal edge of the bottom wall, and cutouts 35 communicate with these slots 34 to define cross-shaped slots for receiving therein the cross bars 22 of the hook members 19, so that the hook members will not rotate when the cross bars are positioned in the slots and cutouts.

From the foregoing it is apparent that a toothbrush-supporting rack has been provided wherein a plurality of toothbrushes can be supported in a neat and sanitary manner. When using the rack of the present invention, the hook members 19 are first connected to the bottom wall 16. Thus, the hook members are arranged as shown in Figure 1, so that the disc 21 engages the upper surface of the bottom wall 16, while the cross bars 22 seat in the slots 17 and cutouts 18. Then, the usual or conventional aperture in the handle of a toothbrush is adapted to have projecting therethrough the fingers 20, whereby the plurality of toothbrushes can be supported, the rack 11 having previously been connected to the shelf 10. In Figure 5, there is shown a rack 25 which is provided with one slot 28 so as to provide a means for supporting only one toothbrush. In Figure 6, there is shown a rack 30 in which is adapted to clamp over the shelf 10 in such a manner that the web 32 is arranged contiguous to the longitudinal side edge of the shelf. The rack 30 of Figure 6 can be used for supporting a plurality of hook members 19 which in turn support the toothbrushes. As previously stated, the hook members 19 are arranged in engagement with the bottom wall 16, and then the rack is connected or clamped onto the shelf.

The racks of the present invention can be made of any suitable material, and also the shape of the slots and cutouts can be varied, if desired. The rack shown in Figures 1 through 4, and the rack shown in Figure 5 are connected to an end of the shelf, while the rack shown in Figure 6 extends lengthwise of the shelf.

I claim:

1. In a supporting rack, a body member having means adapted to be detachably connected to a shelf, the bottom of said body member being provided with a plurality of spaced slots, and a hook member having a disc on its upper end

connected to the body member and projecting through each of said slots.

2. In a supporting rack, a body member having means adapted to be detachably connected to a shelf, the bottom of said body member being provided with a plurality of spaced slots, and a hook member having a disc on its upper end projecting through each of said slots, said hook members being adjustably connected to said body member.

3. In a supporting rack, a body member having means adapted to be detachably connected to a shelf, the bottom of said body member being provided with a slot, and a hook member having a disc on its upper end connected to the body member and projecting through said slot.

4. In combination, a horizontally disposed shelf and a rack for supporting a plurality of toothbrushes, said rack comprising a body member provided with a web, a top wall projecting from said web for engagement with the upper surface of said shelf, a bottom wall projecting from said web for engagement with the lower surface of said shelf, there being a plurality of spaced slots in the shape of a cross arranged in said bottom wall, a plurality of hook members dependingly supported by said bottom wall, each of said hook members comprising a shank having its lower end terminating in a curved finger for engagement with a toothbrush, an annular disc secured to the top of said shank engaging the upper surface of said bottom wall, and cross bars positioned below said disc and secured to said shank seating in said slots.

FRANCIS A. SCHMEDINGHOFF.
